CLARIFICATION OF MOLASSES

Morris W. Mead, Jr., Bloomfield, N. J., assignor
to National Grain Yeast Corporation, Belle-
ville, N. J.

No Drawing. Application April 27, 1936, Serial
No. 76,697

11 Claims. (Cl. 127—48)

The invention relates to the clarification of molasses. The process described herein may be advantageously used wherever it is desired to purify molasses or to make a clear and brilliant molasses. It concerns especially the preparation of molasses suitable for use in the manufacture of yeast by clarification thereof.

Raw molasses always contains certain impurities and suspended matter which are undesirable where it is used as a nutrient in the propagation of yeast. Especially it contains certain iron and calcium compounds which are detrimental when present in excess. Procedures have been suggested and used for treating molasses to remove such deleterious substances. One class of compounds used for clarification of molasses in the past has been the phosphates, that is, the various salts of ortho-phosphoric acid which are the commonest of the phosphates.

The object of the present invention is to provide a process which will give a more complete and economical removal of the impurities contained in molasses, in a shorter time and with the use of less material than any processes heretofore known. The procedure according to the invention is particularly effective in the removal of compounds of the metals such as iron and calcium. It also produces a quicker settling out of the impurities than previously used methods.

I have discovered that a special class of phosphates, namely, pyrophosphates, have unusually advantageous properties as compared to orthophosphates when applied to the clarification of molasses. Pyrophosphates are obtained by the removal of one molecule of water from two molecules of an ortho-phosphate. Pyrophosphoric acid has a chemical formula of $H_4P_2O_7$.

If a pyrophosphoric compound, that is, pyrophosphoric acid or one of its water soluble salts, is added to or dissolved in molasses it will produce a voluminous flocculent precipitation when the molasses is heated. The precipitate so produced settles to the bottom quite rapidly, and the clear supernatant molasses may then be drawn off.

As compared with ortho-phosphates, a considerably reduced quantity of pyrophosphate is required, and yet such reduced quantity produces a considerably larger weight of precipitate. In other words, smaller quantities of pyrophosphate will give the same or better clarification than a larger quantity of ortho-phosphate. The precipitate is of such a nature as to carry down the matter suspended in the molasses more readily and more completely than that formed by an

ortho-phosphate. This precipitate consists of insoluble compounds of certain metals which are present in molasses, together with organic radicals. The pyrophosphates are particularly effective in producing such compounds and thereby in removing excess quantities of the undesirable metals such as iron and calcium.

The general process is applicable both to beet and cane molasses. The general procedure as applied to beet molasses, which as produced normally has a slightly alkaline reaction, is as follows: The raw molasses is diluted with water in the proportion of from 1 to 3 parts by weight of water to 1 part of molasses. A small amount of an acid material, such as sulphuric acid, is added to the diluted mass. Generally from 0.1% to 0.5% by weight on the raw molasses of concentrated sulphuric acid is sufficient. In any event it is desirable to bring the pH of the diluted molasses within a range of 5.2 to 5.8. However, the amount of acid may vary somewhat in accordance with the final acidity desired in the molasses, and in accordance with the type and amount of pyrophosphoric compound added, which will naturally affect to some extent the acidity. In any event the beet molasses is preferably brought to a slightly acidic condition, since in this condition it is more easily purified.

Thereafter, a pyrophosphoric compound is added to the diluted mass and on heating a precipitate forms which settles quickly to the bottom. The clarified molasses which forms a supernatant layer may then be separated from the sludge by decantation or in any other fashion. For example, the precipitate may be filtered through a filter press or in any other manner. It may be run through a centrifuge which is designed to separate the sludge. The use of filtration and centrifuge produces a particularly brilliant product.

Where cane molasses is used, which is normally slightly acidic, but which clarifies more readily when alkaline, the procedure is substantially the same except that a suitable alkaline material is added to bring the pH within the range of 8.0 to 8.5. In addition, a final filtration is desirable when clarifying cane molasses.

When the cane molasses is allowed to settle overnight, it is easy to separate a clear, supernatant liquid from the sludge. However, when this liquid is acidified a slight turbidity reappears, probably because of the presence of very finely dispersed colloidal materials which become readily visible only in acid solution. On the other hand, if the molasses is filtered before it is acidified,

fied it remains brilliant even after the acidification.

The specific procedure for carrying out the invention, and the increased clarification obtained thereby, will be made clear by the examples which follow:

Example 1

Two one-thousand gram batches of raw beet molasses were diluted and treated with equal weights of orthophosphoric acid and pyrophosphoric acid respectively as clarification agents. Five grams of acid, or 0.5% on the molasses, was used in each case. The precipitated solids were filtered off and dried in an oven. The precipitate obtained in the case of pyrophosphoric acid had a weight of 3.8 grams, while with ortho-phosphoric acid its weight was 0.6 grams.

20

Example 2

Equal weights of four different phosphates were added to 500 cc. portions of raw beet molasses which had been diluted with 1.23 parts of water and acidified. The amount of phosphate salt added for clarification purposes was in each case 1.0 gram. The weights of the solid residue obtained as a precipitate are indicated by the following table:

30 Sodium acid pyrophosphate _____ grams 1.145
 Potassium acid orthophosphate _____ do 0.362
 Mono calcium orthophosphate _____ do 0.487
 Commercial clarifier _____ do 0.428
 (orthophosphoric acid and calcium orthophosphate)

Example 3

The following is a preferred procedure for clarifying beet molasses:

40 A batch of raw beet molasses is diluted with water in an amount by weight 1.23 times the weight of the molasses. It is then acidified with 0.3% by weight on the raw molasses of sulphuric acid. 0.2% of sodium acid pyrophosphate ($Na_2H_2P_2O_7$) by weight on the raw molasses is 45 then dissolved in the acidified molasses at room temperature. The mixture is brought to a temperature of 90° C. to 100° C. During the heating a gradual formation of a flocculent precipitate can be observed. The heating is discontinued 50 when the required temperature is reached. The mixture is then allowed to stand for several hours until the precipitate has completely settled. The brilliant supernatant liquid which remains is then decanted.

55

Example 4

The following is a typical procedure for cane molasses:

60 Raw cane molasses is diluted with 1 1/2 times its weight of water. Sufficient lime is then added to bring the pH to within a range of 8.0 to 8.5. 0.2% by weight on the raw molasses of sodium acid pyrophosphate is then added. The mass is heated to from 90° C. to 100° C., allowed to 65 settle, and the clear supernatant liquid decanted. The latter is filtered while still alkaline to avoid a slight turbidity which appears when the molasses is reacidified.

70 The amount of pyrophosphoric compound which is added may vary considerably. Extremely satisfactory clarification has been obtained within a range of from 0.1% to 1.5% by weight on the original raw molasses. The quantity of precipitate apparently increases with a corresponding amount of added pyrophosphate up to

about 1.0%. Above 1.0% the increase in the quantity of precipitate is relatively slight. For economical reasons, a quantity of pyrophosphate ranging from 0.1% to 0.5% on the raw molasses is most satisfactory. Larger amounts of pyrophosphate produce inconveniently large quantities of sludge, without a proportionate gain in the amount of clarification, and are uneconomical. Within the range of 0.15% to 0.2% a sufficient and satisfactory settling out of the precipitate is obtained.

10 The acidity of the solution also affects the amount of precipitation obtained with pyrophosphate. In the treatment of beet molasses, excessive acidity will decrease the amount of precipitation. The following data represent tests in which 2.5 grams of sodium acid pyrophosphate was added to four 1900 cc. portions of diluted molasses at different acidities:

Final pH	Dry weight of sludge
5.74	2.9 gm.
5.80	2.7 gm.
5.20	2.55 gm.
4.97	2.3 gm.

I have found that pyrophosphoric acid and its soluble salts are all effective in the clarification of molasses. Especially effective are the acid itself and sodium acid pyrophosphate, ammonium pyrophosphate, and tetra-potassium pyrophosphate. The tetra-potassium pyrophosphate is even more active than the sodium acid pyrophosphate used in the examples described above.

30 The process above described produces a molasses which is lighter in color and somewhat more brilliant than that clarified with orthophosphates. It is very satisfactory for the propagation of yeast, and good yields of yeast are obtained with its use which have good color and baking quality.

40 The procedure therefore provides an economical and effective method of clarifying molasses for yeast propagation or other purposes in a short time and with the use of small quantities of materials.

45 While I have described herein some embodiments of my invention, I wish it to be understood that I do not intend to limit myself thereby except within the scope of the appended claims.

50 I claim:

55 1. In a process of clarifying molasses, the steps of adding thereto a compound selected from the group consisting of pyrophosphoric acid and its soluble salts, heating the molasses until a precipitate is formed therein, and then separating the molasses from the precipitate.

60 2. In a process of clarifying molasses, the steps of adding thereto a compound selected from the group consisting of pyrophosphoric acid and its soluble salts, heating the molasses until a precipitate is formed therein, allowing the precipitate to settle, and decanting the supernatant liquid.

65 3. In a process of clarifying molasses, the steps of adding thereto a compound selected from the group consisting of pyrophosphoric acid and its soluble salts, heating the molasses to a temperature of from 90° C. to 100° C., whereby a precipitate is formed in the molasses, and separating the molasses from the precipitate.

70 4. In a process of clarifying beet molasses, the steps of acidifying the beet molasses, adding

75

thereto a compound selected from the group consisting of pyrophosphoric acid and its soluble salts, heating the molasses until a precipitate is formed therein, and then separating the molasses from the precipitate.

5. In a process of clarifying cane molasses, the steps of rendering the molasses alkaline, adding thereto a compound selected from the group consisting of pyrophosphoric acid and its soluble salts, heating the molasses until a precipitate is formed therein, and then separating the molasses from the precipitate.

10 6. In a process of clarifying molasses, the steps of adding thereto from 0.1% to 1.5% of a compound selected from the group consisting of pyrophosphoric acid and its soluble salts, heating the molasses until a precipitate is formed therein, and separating the supernatant liquid from the precipitate.

15 7. In a process of clarifying molasses, the steps of diluting the molasses with water, adding thereto a compound selected from the group

consisting of pyrophosphoric acid and its soluble salts, heating the molasses until a precipitate is formed, and then separating the molasses from the precipitate.

8. In a process of clarifying molasses, the steps 5 of diluting the molasses with from 1 to 3 parts by weight of water, dissolving in the diluted molasses from 0.1% to 1.5% of a compound selected from the group consisting of pyrophosphoric acid and its soluble salts, heating the 10 molasses to from 90° C., to 100° C., whereby a precipitate is formed therein, allowing the precipitate to settle, and decanting the remaining supernatant liquid from the precipitate.

9. A process as claimed in claim 1, in which 15 said compound is pyrophosphoric acid.

10. A process as claimed in claim 1, in which said compound is sodium acid pyrophosphate.

11. A process as claimed in claim 1, in which said compound is tetrapotassium pyrophosphate. 20
